FREDRICK J. RODE, OF CHICAGO, ILLINOIS, ASSIGNOR TO MARQUETTE TOOL & MFG. COMPANY, OF CHICAGO, ILLINOIS, A CORPORATION OF ILLINOIS

SPRING CUSHION FOR PRESSES

Application filed January 30, 1929. Serial No. 336,303.

This invention relates to improvements in spring cushion for presses, particularly adapted, though not necessarily limited in its use, with sheet metal presses.

In presses of this character there is usually employed a die or work holding element which is movable under the action of a reciprocable ram. A pressure pad or plate is also usually employed which is movable with said die or work holding element and the pad is resisted in its movement in one direction by a cushion formed of springs, and the desired amount of resistance has been obtained by providing a sufficient number of springs.

In some instances and in order to produce the desired amount of resistance pressure to the pad, a plurality of springs have been superposed, which requires a considerable amount of space in the form of a deep pit under the press to accommodate the springs. This is objectionable inasmuch as it sometimes becomes necessary to adjust the springs and it has been very inconvenient and sometimes almost impossible for the workmen to gain access to the springs or parts of the press which are located in the deep pit.

Furthermore the rate of increase of pressure on long springs is less than that of short springs, therefore it has been necessary heretofore, in order to get the desired pressure, to superpose the springs or arrange them end to end.

It is one of the objects of the present invention to provide an improved spring cushion of this character in which short springs may be employed by arranging or locating the springs beside each other, with all of the springs disposed above the floor, thereby materially reducing the depth of pit necessary, and at the same time the springs will have the same effect as if they are superposed, and the springs and co-operating parts will be readily accessible.

To the attainment of these ends and the accomplishment of other new and useful objects as will appear, the invention consists in the features of novelty in substantially the construction, combination and arrangement of the several parts hereinafter more fully described and claimed and shown in the ac-

companying drawings illustrating this invention, and in which

Figure 1 is a view partly in front elevation, partly in section, and partly broken away of a sheet metal press having a spring cushion constructed in accordance with the principles of this invention applied thereto. 55

Figure 2 is a detail sectional view taken on line 2-2, Figure 1, with the parts of the spring cushion in one position. 60

Figure 3 is a view similar to Figure 2, with the parts in another position.

Figure 4 is a detail top plan view of the housing or abutment member for the springs. 65

Referring more particularly to the drawings the numeral 10 designates the bed of a press, 11 the uprights, 12 a reciprocable ram, 13 a reciprocable die member connected with the ram, 14 a die member with which the die 13 co-operates, 15 the bed or bolster plate of a press, 16 a pressure pad or pin plate and 17 pins or members which support the die 14 and which loosely pass through the bed or bolster plate 15 and engage and rest upon the pressure pad 16. 70 75

All of the above referred to parts are of the ordinary and well known construction.

Disposed below the bed of the press is a support 18 which may be held in position in any desired or suitable manner preferably by 80 means of rods or hangers 19 engaging a stationary part of the press.

Interposed between the support 18 and the bolster plate 15 and beneath the pressure pad 16, is a spring housing or abutment member 20, any number of which may be provided according to the number of springs necessary and the size of the press. 85

This housing or abutment member floats between the support 18 and the bolster plate 15 and is supported by means of springs 21, one end of which engage and rest upon the support 18. 90

The springs 21 are arranged side by side 95 and are maintained against displacement in any suitable manner preferably by means of rods or members 22, one end of each of which is secured to the support 18 preferably by passing therethrough and upon the ends of 100

which rods beneath the support are nuts or collars 23.

The housing or member 20 is provided with recesses 24 opening through the lower face 5 thereof and into which recesses the springs 21 extend, the upper ends of the springs abutting the bottom of the respective recesses. The rods 22 pass loosely through the top of the member 20 and the pressure pad 16 may be 10 provided with recesses 25 opening through its bottom face in alignment with the ends of the rods 22 so that when the pressure pad 16 is lowered the ends of the rods will enter these recesses and thereby not interfere with 15 the lowering movement of the pressure pad.

The housing or abutment member 20 is also provided with recesses 26 opening through its upper face and any number of these recesses 26 may be provided, according to the number 20 of springs to be employed. Secured to and depending from the pressure pad 16 are rods 27 which pass through the respective recesses 26 and also through the bottom of the recesses 25 and project beyond the lower face of the member 20. These rods 27 also pass through suitable openings in the support 18 whereby the support 18 will form a guide for the lower ends of the rods. Encompassing each of the rods 27 is a spring 28, one end of each of which 30 abuts the bottom of the respective recesses 26 and the other ends abut the bottom of the pressure pad or plate 16, the springs 28 encompassing the respective rods 27 and through which springs the rods 27 are freely 35 movable.

Obviously the shape of the member 20 will be determined by the number of springs employed.

With this improved construction it will be 40 manifest that the housing or abutment member 20 will be supported for free or floating movement between the bolster plate 15 and the support 18.

It will also be manifest that with this construction the springs may be arranged side 45 by side and the necessity of a deep pit will be obviated, it only being necessary to provide a comparatively shallow pit 29 in which the ends of the rods 27 project when the pressure 50 pad 16 is lowered.

In operation, the pressure pad 16 will be maintained in its uppermost position as shown in Figure 2, when the press is not in operation, by the stress of the springs 21 and 55 28. The normal tendency of the springs 21 is to elevate the housing or abutment plate 20 while the springs 28 in turn have a normal tendency to return the pad 16 to its normal position and hold the same in such position until 60 it is depressed.

When the ram descends and the die member 14 is depressed the pressure pad 16 will also be depressed through the medium of the pins 17 tending to compress the springs 28 65 and thereby lower the housing or abutment

member 20. The lowering movement, however, of the housing is resisted by the action of the springs 21 being compressed by such movement of the housing or member 20, thereby producing the required and a predetermined amount of resistance against the lowering movement of the pressure pad 16. All of the springs are of substantially the same resistance stress, with the result that there will be an even blank holding pressure 75 throughout the cycle of movement of the pressure pad against the stress of the springs, which is of great importance in machines of this character.

It will also be manifest that the springs 80 will be disposed above the floor and will be readily accessible.

By varying the number of springs and by varying the strength of the springs, the desired resistance pressure may be obtained and the same effect will be produced by the present arrangement as would be produced if the springs were superposed, but with the present invention the necessity of a deep pit 85 is obviated.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. In combination, a press, a reciprocable ram, a pressure pad with which the ram cooperates, a cushion for resisting the movement of the pad in one direction, said cushion embodying an abutment member, a fixed support, and between which support and pad said member is disposed, springs, the opposite ends of which engage the said abutment member and said pad, and additional springs, the opposite ends of which latter respectively engage said abutment member and said support, all of said springs being of substantially the same resistance stress.

2. In combination, a press, a reciprocable ram, a pressure pad with which the ram cooperates, a cushion for resisting the movement of the pad in one direction, said cushion embodying an abutment member, a fixed support, and between which support and pad said member is disposed, springs, the opposite ends of which engage the said abutment member and said pad, and additional springs, the opposite ends of which latter respectively engage said abutment member and said support, the said abutment member being yieldingly supported by the last recited springs, all of said springs being of substantially the same resistance stress.

3. In combination, a press, a reciprocable ram, a pressure pad with which the ram cooperates, a cushion for resisting the move-

ment of the pad in one direction, said cushion embodying an abutment member, a fixed support, and between which support and pad said member is disposed, springs, the opposite ends of which engage the abutment member and said pad, and additional springs, the opposite ends of which latter respectively engage said abutment member and said support, the proximate portions of said springs being housed within said abutment member, all of the springs being of substantially the same resistance stress.

4. In combination, a press, a reciprocable ram, a pressure pad with which the ram operates, a cushion for resisting the movement of the pad in one direction, said cushion embodying an abutment member, a fixed support, and between which support and pad said member is disposed, springs, the opposite ends of which engage the abutment member and said pad, and additional springs arranged out of alinement with the first said openings, the opposite ends of which latter respectively engage said abutment member and said support, all of said springs being of substantially the same resistance stress.

5. A spring cushion for presses, said cushion embodying a floating abutment member, a plurality of springs arranged side by side, all of said springs being of substantially the same resistance stress, one end of each of the springs engaging said abutment member, the other ends of some of the springs engaging a stationary element on one side of the said member, and the other ends of others of the springs engaging a movable member on the side of the abutment member opposite to said stationary element and which movable member is movable towards the said stationary element.

6. A spring cushion for presses embodying a stationary support, a pressure pad spaced therefrom and movable towards and away from the support, a set of springs one end of which engage said support and extend towards and terminate short of said pad, a set of springs one end of which engage said pad and extend towards and terminate short of said support, and a floating abutment member interposed between the other ends of the two sets of springs and engaged thereby whereby both sets of springs will be compressed when said pad is moved towards said support, all of said springs being of substantially the same resistance stress.

7. A spring cushion for presses embodying a stationary support, a pressure pad spaced therefrom and movable towards and away from the support, a set of springs one end of which engage said support and extend towards and terminate short of said pad, a set of springs one end of which engage said pad and extend towards and terminate short of said support, and a floating abutment member interposed between the other ends of the

two sets of springs and engaged thereby whereby both sets of springs will be compressed when said pad is moved towards said support, the respective springs of the sets being out of alinement and substantially parallel with each other, all of said springs being of substantially the same resistance stress.

8. A spring cushion for presses embodying a stationary support, a pressure pad spaced therefrom and movable towards and away from the support, a floating abutment member interposed between the support and pad and spaced from both, said member having recesses opening through opposite faces thereof, springs seated in the recesses which open through one face of the member and engaging said support, and springs seated in the recesses which open through the opposite face of the abutment and engaging the said pad, whereby when said pad is moved towards said support, all of said springs will be compressed, all of said springs being of substantially the same resistance stress.

9. A spring cushion for presses embodying a stationary support, a pressure pad spaced therefrom and movable towards and away from the support, a floating abutment member interposed between the support and pad and spaced from both, said member having recesses opening through opposite faces thereof, the recesses opening through one face of the abutment being out of alinement with the recesses opening through the other face thereof, springs seated in the recesses which open through one face of the member and engaging said support, and springs seated in the recesses which open through the opposite face of the abutment and engaging the said pad, whereby when said pad is moved towards said support, all of said springs will be compressed, all of said springs being of substantially the same resistance stress.

10. A spring cushion for presses embodying a stationary support, a pressure pad spaced therefrom and movable towards and away from the support, a floating abutment member interposed between the support and pad and spaced from both, said member having recesses opening through opposite faces thereof, springs seated in the recesses which open through one face of the member and engaging said support, and springs seated in the recesses which open through the opposite face of the abutment and engaging the said pad, whereby when said pad is moved towards said support, all of said springs will be compressed, the said springs being arranged side by side, all of said springs being of substantially the same resistance stress.

11. A spring cushion for presses embodying a stationary support, a pressure pad spaced therefrom and movable towards and away from the support, a floating abutment member interposed between the support and pad and spaced from both, springs arranged

on opposite sides of and engaging said abutment, the springs on one side of said abutment also engaging the said support and the springs on the other side of the abutment 5 also engaging said pad, whereby when the pad is moved towards said support the stress of all of said springs will be exerted upon said pad, all of said springs being of substantially the same resistance stress.

10 12. A spring cushion for presses embodying a stationary support, a pressure pad spaced therefrom and movable towards and away from the support, a floating abutment member interposed between the support and pad 15 and spaced from both, and springs arranged on opposite sides of and engaging said abutment, the springs on one side of said abutment also engaging the said support and the springs on the other side of the abutment also 20 engaging said pad, whereby when the pad is moved towards said support the stress of all of said springs will be exerted upon said pad, the springs on one side of the abutment being out of alignment with and overlapping the 25 springs on the opposite side thereof, all of said springs being of substantially the same resistance stress.

In testimony whereof I have signed my name to this specification, on this 25th day 30 of January, A. D. 1929.

FREDRICH J. RODE.
